FIG. 4.

UNITED STATES PATENT OFFICE

2,060,456

LUBRICATING APPARATUS

Frank S. Barks, St. Louis, Alexander P. Fox, University City, and William Z. Linders, Normandy, Mo., assignors to Lincoln Engineering Company, St. Louis, Mo., a corporation of Missouri

Original application October 13, 1934, Serial No. 748,188, now Patent No. 2,010,174, dated August 6, 1935. Divided and this application August 3, 1935, Serial No. 34,494

3 Claims. (Cl. 285—161)

This invention relates to lubricating apparatus, and with regard to certain more specific features, to a gun for forcing lubricant under pressure into receiving fittings and the like.

5 This is a division of the invention disclosed in our application Serial Number 748,188, filed October 13, 1934, for Lubricating apparatus, eventuated into United States Patent 2,010,174, dated August 6, 1935.

10 Among the several objects of the invention may be noted the provision of a lubricator hand gun which may be conveniently and quickly guided on to and applied without substantial leakage to successive fittings, and quickly operated to provide a substantially high lubricant pressure, and which may be quickly removed; the provision of a lubricating gun of the class described, which has interchangeable nozzles, each particularly adapted for a given class of work but each of which may be operated with equal convenience in its respective class of work; the provision of a lubricating gun of the class described which is light and compact enough to be used with one hand, if desired, but not necessarily so, the same carrying a substantial charge of lubricant; and the provision of apparatus of this class which is convenient in form and economical to manufacture. Other objects will be in part obvious and in part pointed out herein-after.

30 The invention accordingly comprises the elements and combinations of elements, features of construction, and arrangements of parts which will be exemplified in the structures hereinafter described, and the scope of the application of which will be indicated in the following claims.

In the accompanying drawing, in which are illustrated several of various possible embodiments of the invention,

40 Fig. 1 is a longitudinal section taken through the apparatus, showing one form of nozzle;

Fig. 2 is an enlarged longitudinal section of one class of fitting to which the apparatus may be applied;

45 Fig. 3 is an enlarged longitudinal section showing an alternative form of nozzle; and,

Fig. 4 is a vertical cross section taken on line 4—4 of Fig. 3.

Similar reference characters indicate corresponding parts throughout the several views of the drawing.

Referring now more particularly to Fig. 1, there is shown at numeral 1 a barrel-shaped body in which is a main bore 3 for slidably accommodating a plunger 5, said bore 3 having an in-

let 7 just ahead of the rearmost position of said plunger 5. The inlet 7 is covered by the plunger 5 when the latter is forced forwardly. Said inlet 7 widens out and slopes rearwardly and downwardly, the same being finally formed as an angular cap 9 which is integral with the body portion 1.

The cap 9 is threaded to detachably receive an angularly located lubricant supply cylinder 11. The cylinder 11 has a lower cap 13 through which is formed an opening 15. Within the cylinder 11 is a free piston 17. To load the supply cylinder 11, the free piston 17 is forced downwardly against the cap 13, thus covering the opening 15. The cylinder 11 is then filled and screwed to the cap 9. Upon reciprocation of the plunger 5 and withdrawal of lubricant through the inlet 7, the supply in the cylinder is gradually exhausted and the piston 17, under atmospheric pressure through opening 15, follows the exhausting supply.

Rearwardly, the body 1 is provided with a stationary grip 19, the latter being held in place on the body 1 by means of a threaded bushing 21. The rear end of the plunger 5 is fastened to a guide stem 23, the latter passing slidably through the opening of said bushing 21 and into a rearward counterbore 25. The counterbore 25 is somewhat larger in diameter than said guide stem 23. A packing 27 is used between the guide stem 23 and said rearward counterbore 25 to seal against leakage.

At its rearward end the guide stem 23 is provided with a movable handle 29 which is similar in shape to the stationary handle 19. A spring 31 reacts between the bushing 21 and said movable handle 29. The handles 19 and 29 are of dome-like shape. They are so formed that when separated fingers are placed under the stationary handle 19, the palm of the hand may be used for pressing inwardly the movable handle 29. This permits of supporting and operating the device with one hand. Of course, if desired, the other hand may aid the operation by gripping the supply chamber 11, although this is not necessary. The cylinder 11 then functions as a convenient grip.

At its forward end, the body 1 is provided with stepped counterbores 33 and 35, the former accommodating a relatively soft packing 37 and the latter a ball check valve 39, normally held in seated position by a spring 41. The spring 41 reacts against said packing 37.

In the opening at the opposite end of the packing 37 is positioned a cylindric extension 43

of a delivery nipple 45, said nipple having a flange 47 which has a flat face where it engages the packing 37, but which is provided with a beveled portion 48 opposite the packing. The beveled portion provides a rocking edge 51 adapted to cooperate with the inner flat surface of a metal retaining washer 53 held in place on the end of the body 1 by means of a threaded sleeve 55. The extension 43, flange 47 and nipple 45 are 10 hollow to form a conduit.

Further details in regard to the rocking action of the flange 47 on the inner face of the member 53 may be obtained from the United States Patent 1,947,208 of William Z. Linders (see Fig. 15 3 therein). In general, the edge of the flange 47 clears the bore 33 enough to permit rocking of the edge 51 on said washer 53. There is enough clearance between the hole through the washer 53 and the nipple tip 45 to permit of this action. 20 It is to be understood that the rocking action is of a magnitude which, relative to the purpose in hand, is enough to permit of some angularity of the body 1 with respect to the nipple 45. Since the nipple 45 may rock slightly in the end of the 25 fitting 56, the angle of the body 1, with respect to the fitting 56, is the sum of the angle of the body 1 with respect to the nipple 45 and that of the nipple 45 with respect to the fitting 56. Hence a smaller nipple angle is required for a 30 given body angle, both measured with respect to the fitting 56.

The fitting comprises a hexagonal portion 57 back of which is a screw threaded portion 59 for screw connecting the fitting to passages which 35 are to be lubricated. Ahead of the flange 57 extends a cylindric receiving tip 61, grooved as shown at 63 and provided with an inlet portion 65 which is substantially semi-spherical or convex in form. The groove 63 constitutes a reduced 40 neck portion. An inlet bore 67 communicates with a central counterbore 69, and said counterbore 69 communicates with a rearward and larger bore 71. A ball check valve 73 seats against the end of the counterbore 69 and is 45 normally held in position by means of a coil spring 75 reacting from an inwardly directed flange 77.

It will be seen that the symmetrical guide sleeve 55 is hollow interiorly and is provided endwise with an inwardly extending flange 79. This flange is preferably beveled as at 82 on its inward side. The groove 63 is beveled on its forward side, as shown at numeral 81 and may be beveled at 83, as shown, although the latter bevel 55 is not important. The bevels 81 and 82 cooperate to provide clearance as will appear.

The clearance between the opening through flange 79 and the base of the spherical portion 65 of the fitting 56 is such as to provide a loose 60 or free, guiding fit. The opening through the flange is substantially equal to the fitting diameter at the bottom of the convex head portion but slightly larger for free clearance. Thus, as the gun is pressed on the fitting 56, the flange 79 effects a guiding action over the portion 65. A 65 nicety of aim in applying the gun to the fitting is not necessary. As the nipple 45 enters the opening 67 in the fitting 56, a seal is effected and the guiding action of the flange 79 ceases, because 70 said flange 79 comes opposite the groove 63. Hence, thereafter, considerable free rocking of the body 1 may be effected with respect to the fitting 56 without tending to loosen the lubricant-tight pressure seal between the nipple 75 45 and the interior of the opening 67.

Merely to provide a guide for sending the nipple 45 into the opening 67 is not enough. This is because after the nipple has been guided home, the ordinary guiding structure will effect a second point of rocking which will loosen the nipple 45 from that with which it engages, when the body 1 is inadvertently rocked, as when effecting a pumping action on the handle 29. With the present invention, full guiding action is obtained in applying the apparatus for attachment to the 10 fitting and after it has been contacted, the guiding action ceases and permits ample rocking about one center only at the end of the fitting without prying action about some other center, which would loosen the sealing contact. The 15 bevels 81 and 82 cooperate to insure proper clearance between flange 79 and groove 63.

It is to be understood that as the body 1 rocks (inadvertently) angularity is effected between the nipple 45 and said body and also angularity 20 is effected between the nipple and the fitting. As above shown, the purpose of allowing the angularity between the nipple and the body is to reduce the angularity between the nipple and the fitting, with an overall angularity between 25 the body 1 and fitting 55 which is of the order of that which obtains when a pumping action goes on. The flange 79 and groove 63 take care of this overall rocking without prying the nipple 45 from the opening 67.

In operation, assuming the chamber 11 to be filled, the operator grasps the separated handles 19 and 29 and applies the sleeve 55 to the fitting 56. The flange 79 cooperates, first with the spherical end 65 of the fitting. Only an approximate alignment is necessary because, as the gun is further pressed to the fitting, the flange 79 rides toward the cylinder 69 over the end 65 and guides the nipple 45 into the opening 67. After this has occurred, the flange 79 comes opposite 40 the groove 63. The operator then presses the handle 29 toward the handle 19 repeatedly, thus effecting ejection of lubricant from the nipple 45 and into the fitting 56. Any rocking action of the body 1, engendered by the pumping action 45 between handles 19 and 29 is provided for without effecting a disconnection between nipple 45 and fitting 55, for the reason above given. As the supply in the chamber 11 is reduced, the piston 17 follows under atmospheric pressure to main- 50 tain a supply at the inlet 7.

Referring now more particularly to Fig. 3, it will be seen that the barrel 1 is alternatively provided with a threaded sleeve 85 which holds in position a split sleeve 89 having a head member 87. However, instead of using the inwardly extending flange 79 of Fig. 1, the outer end of the sleeve 85 is bored straight for receiving the inner split sleeve 89 whereby the sleeve 89 and said head 87 may be held in place at the end of 60 the body 1 and spaced around the nipple 45.

The bore through the split sleeve 89 and the outside diameter of said sleeve 85 are arranged, for example, as follows:

Assuming that the outside diameter of the 65 cylindric portion 61 and base of head 65 of the fitting is .249 inch, the sleeve 89 is formed with a bore in its unstrained condition which is .250 inch. The sleeve is then closed in so that its final inside dimension is .249 inch. It is then hardened. This leaves no clearance between the split sleeve 89 and fitting 56. The clearance between the outside diameter of the sleeve 89 and the inside diameter of the sleeve 85 is .002 inch.

The result of the above relationship is that 75

there is an accurate sliding fit between the split sleeve 89 and the cylindric portion 61 of fitting 56 which effects a definite alignment, so that the cylinder 1 cannot be rocked under any condition 5 to any degree which would loosen the nipple 45 from its position in the receiving opening 67, after application of the gun to the fitting. The springing action of the split sleeve 89 assures a snug, sliding, frictional fit. At the same time, there is 10 not so much clearance between the outside of the sleeve 89 and the inside of the sleeve 85 that a permanent set can be effected in sleeve 89 by repeated application of the device to fittings. That is to say, if a split sleeve were used, without 15 being suitably backed, it would soon take on a permanent set and thereby become loose. If it were tightly backed up there would be no spring at all and the snug application could not, in practice, be brought about in the first instance. 20 While it is not desired that we be limited to the above dimensions, they are given as being exemplary of the proportions desired. The functions to be effected by the proportions are a snug, sliding, frictional fit interiorly between the split 25 sleeve 89 and the tip of the fitting and at the same time a backing of the split sleeve by a rigid member 85 at such a distance that some springing may be effected without the split sleeve taking a permanent set, that is, without being stressed 30 beyond its elastic limit.

The sleeves 55 and 85 and included parts are interchangeable. The sleeve 85 of Fig. 3, which maintains a rigid alignment between fitting and gun, is most useful in applications where it is 35 desired to be able to attach a gun to the fitting and have it remain there temporarily while the operator effects maneuvers. For instance, if the car which is being lubricated is not jacked up, this form of sleeve is preferable because an attachment to the nipple may be made and then the operator's body placed in an advantageous position to effect pumping. Analogous situations 40 will suggest themselves.

The form of the sleeve shown in Fig. 1 is preferable 45 where the car is raised and the operator can get beneath it, such that application of the gun and a pumping stroke may be made simultaneously but at somewhat various angles with respect to the fitting. The sleeve of Fig. 1 is also somewhat preferable for use with power 50 pumps having flexible outlets reaching up to the ball check 39, instead of the hand pump. This is because the outlets of power guns are not rigid and it is therefore more difficult to maintain a direct alignment with the fitting. Furthermore, 55 the parts associated with the power coupler and hose are ordinarily so heavy that a sleeve such as shown at Fig. 3 would have an undue bending moment applied to it. However, it is not to be understood that the structure of Fig. 3 is not applicable to power guns, because under proper 60 conditions of design it is also useful for the purpose.

In view of the above, it will be seen that the

several objects of the invention are achieved and other advantageous results attained.

As many changes could be made in carrying out the above constructions without departing from the scope of the invention, it is intended 5 that all matter contained in the above description or shown in the accompanying drawing shall be interpreted as illustrative and not in a limiting sense.

We claim:

1. In apparatus of the class described, in combination with a fitting having a substantially cylindric contour behind its forward end, an outer sleeve and an inner sleeve within said outer sleeve, said inner sleeve being split and interiorly cylindric and being springingly engageable with the cylindric contour of said fitting to effect a snug and aligned attachment without supplemental pressure on the split sleeve, the clearance between the inner and outer sleeves being fixed and of 20 an order adapted to permit outward springing action of the inner sleeve but limiting its expanding movement to a degree which will avoid permanent strain under repeated applications.

2. In apparatus of the class described, in combination with a fitting having a substantially cylindric contour behind its forward end, an outer sleeve, and a separate, inner sleeve within said outer sleeve, said inner sleeve being split and interiorly cylindric and being springingly engageable with the cylindric contour of said fitting to effect a snug and aligned attachment without supplemental pressure on the split sleeve, the clearance between the inner and outer sleeves being fixed and of an order adapted to permit 25 springing action of the inner sleeve but limiting its movement to a degree which will avoid permanent strain under repeated applications, the split inner sleeve and outer sleeve being relatively 30 fixed longitudinally.

3. In apparatus of the class described, in combination with a fitting having a receiving opening with a substantially cylindric contour behind its forward end, an outlet nipple adapted to cooperate interiorly with said opening in the fitting, an outer sleeve positioned about said nipple, and a separate inner sleeve within said outer sleeve, said inner sleeve being split and being springingly engageable with said fitting, the clearance between the inner and outer sleeves being of an order adapted to permit springing action of the inner sleeve but limiting its expanding movement to a degree which will avoid permanent strain under continued application, and means mounting 45 the nipple in connection with lubricant supply means so that there is angular movement between the two without leakage, whereby the angular movement between the supply means and the fitting may be greater than that between the nipple and the fitting.
